(57) **CLAIM**

The ornamental design for an airplane/model airplane as shown and described.

DESCRIPTION

FIG. 1 is a top, front perspective view of an airplane/model airplane showing a first embodiment of my new design;

FIG. 2 is a top plan view thereof;

FIG. 3 is a rear elevational view thereof;

FIG. 4 is a bottom plan view thereof;

FIG. 5 is a front elevational view thereof;

FIG. 6 is a left side elevational thereof;

FIG. 7 is a right side elevational view thereof;

FIG. 8 is a top, front perspective view of an airplane/model airplane showing a second embodiment of my new design;

FIG. 9 is a top plan view thereof;

FIG. 10 is a rear elevational view thereof;

FIG. 11 is a bottom plan view thereof;

FIG. 12 is a front elevational view thereof;

FIG. 13 is a left side elevational thereof; and,

FIG. 14 is a right side elevational view thereof.

1 Claim, 14 Drawing Sheets
